UNITED STATES PATENT OFFICE.

FRANK C. DORMENT, OF CLEVELAND, OHIO, ASSIGNOR OF ONE-HALF TO GEORGE J. LOWE, OF CLEVELAND, OHIO.

VAPORIZING DEVICE.

Application filed August 11, 1920. Serial No. 402,884.

To all whom it may concern:

Be it known that I, FRANK C. DORMENT, a citizen of the United States, residing at Cleveland, in the county of Cuyahoga and 5 State of Ohio, have invented a certain new and useful Improvement in Vaporizing Devices, of which the following is a full, clear, and exact description.

The present invention relates to a vaporizing device which is particularly designed to vaporize liquid material used as a deodorant, disinfectant or medicinal remedy useful in the treatment of the human respiratory passages.

15 The device finds particular utility as an apparatus for deodorizing and purifying the air in buildings, theaters and similar assembly halls, and because of the efficiency of the vaporizing action obtained, the vaporized 20 material is disseminated rapidly and extensively.

Thorough vaporization is obtained not only by mechanically breaking up the particles of the liquid used, but the heat generated by the motor of the suction and expelling fan is utilized to heat the exit portion of the device and effect a further and more complete vaporizing action.

The foregoing objects are accomplished 30 while maintaining the proportions of the device as to make the same of simple as well as light construction and readily portable.

Reference should be had to the accompanying drawings forming a part of this 35 specification in which Fig. 1 is a sectional elevation; Fig. 2 is a bottom plan view; Fig. 3 is a top plan view of a portion of the machine; Fig. 4 is a plan view of the suction fan; Fig. 5 is a plan view of the top plate 40 of the receptacle.

Referring to the drawings, 1 indicates a container which has a side wall portion; a top wall 2 and a bottom 3 which is preferably made with a raised central portion so 45 that the liquid contents of the container will have a tendency to flow toward the outer edge thus enabling the last portions of the liquid which may be used in the container to be utilized.

50 Depending from the cover 2 is a partition member 4 which extends parallel with the side wall of the container to a point adjacent the bottom member 3. This partition member forms an air conducting chamber 55 which may be designated at 5, which air

conducting chamber extends entirely around the inner wall of the container.

The top member 2 is provided with a plurality of slot like openings such as indicated at 6, and controlling these openings is a 60 cover member 7 which is mounted to have a turning member on the top 2. The top member 2 has an upstanding collar 2^a and the cover member has an upstanding flange 7^a. These are in engagement and the cover member 7 turns about the upstanding flange 2^a. The cover is provided with a plurality of openings such as indicated at 7^b and inasmuch as the cover 10 may be turned, the openings 7^b and 6 may be brought into registry so as to make a free opening for the passage of air. Obviously the cover 7 may be adjusted so as to effect a partial aligning of the openings 6 and 7^b and this may be effected to any desired extent to control the 75 passage of air through the openings described.

The upstanding flange 2^a which is formed as a part of the cover 2 receives a casing which may be generally indicated at 8. 80 This casing has a tubular extension 9 which fits within the upstanding flange 2^a. This casing is formed preferably in two halves, as indicated at 8^a and 8^b, these two halves being secured together 85 by any suitable means. Within the casing is a fan such as indicated at 10, the fan being preferably arranged so that its axis is substantially in line with the annular or circular neck portion 9. The portion 8^a of the casing 8 has an extending portion 8^b which is of a proper size to receive the stator and rotor of a motor for operating the fan. The motor shaft is extended so that the fan may be mounted upon the same as indicated at 90

11. Inasmuch as the portion 8^a of the casing is made integral with the portion 8^b, the heat which is generated incident to the use of the motor, will be conducted by the sleeve like extension 8^b from the motor to the casing 8 and inasmuch as by the action of the fan air is passing through the casing 8, the heat is conducted by the air from the casing 8.

105 This action results in a two fold usefulness. In the first place the motor runs cool so that if the apparatus be operated for considerable periods of time, there is no danger of overheating the motor. This is an important consideration when it is 110

remembered that in a device of this character the motor cannot be large and must be positioned with respect to a proper placement of the fan which it operates, and furthermore, through the necessity of positioning the motor on top as it were of the apparatus, it is desirable to protect the motor against accidental damage. Accomplishing all these results and at the same time conducting the heat away from the motor is an item of considerable importance.

Additionally, however, the heat which is thus disseminated through the casing 8 serves to heat to a slight extent the vapor laden air which is being forced by the fan and the heat which is thus imparted to the vapor laden air serves to more effectively vaporize the material with which the air is laden.

The casing 8 is provided with an exit end 8^a which is arranged substantially tangential to the periphery of the fan. This exit portion 9^b may be left open as it is in the case where the apparatus is being used for the purpose of disinfecting and purifying the air in a room or hall or building, but when it is desired to use the apparatus in the treatment of diseases of the respiratory passages a plug 13 may be inserted in the part 8^a which plug carries a hose 14 with a mask 15, which mask is placed over the mouth and nose of the patient being treated.

Within the wall 4 there is a depending screen member 16. This is preferably cylindrical in shape and the lower end is closed preferably by means of a conical bottom piece 19. This form of bottom piece is advantageous in that if some particles of liquid pass through the screen 16, and collect within the screen member, the particles of liquid will not tend to collect within the tube, but rather will flow down the slanting walls 17 and return to the body of liquid within the container. The cylindrical screen member 16 is fastened to a collar 18 which is frictionally held within the portion 9 of the casing 8.

It will be seen that the casing 8 and the screen member 16 may be removed as a unit from the container, and also the casing 8 being made in two parts, permits ready access to all the working parts of the apparatus.

The bottom member 3 of the container is removable and is held to the side wall portion of the container by means of clamping members such as indicated at 19 which are held in place by screws 20.

In the operation of the device the liquid to be vaporized is placed within the container 1 and a sufficient portion is placed therein so as to seal the lower end of the partition 4. The fan is started and creates a suction within the wall 4 which draws

air through the openings 7^b and 6 and through the air passageway 5, which air bubbles up through the liquid in the bottom of the container and as it bubbles up the air becomes laden with the vapors and small particles of the liquid through which it is passed.

The vapor laden air next passes through the screen member 16 which serves to break up the particles of liquid which may be mechanically carried by the air and generally to cause a more thorough mixture of the air and the vapor. The vapor laden air as it passes through the casing 8, takes up the heat which has been conducted to it from the portion of the casing which surrounds the motor and so provides an increased assistance to secure complete vaporization.

Having described my invention, I claim:

1. A vaporizing device comprising a container adapted to contain a liquid and having a top with an opening therein, a casing having a downwardly extending flange which fits within the opening in the top so that the same is removable from the container and the interior of the casing communicating with the interior of the container said casing having an air outlet, a downwardly extending cylindrical strainer carried by said flange and removable with the casing from the container, a fan within said casing said casing being provided with a sleeve portion, a motor within said sleeve portion, and means for conducting air from outside of the container to adjacent the bottom of said container.

2. A vaporizing device comprising a container adapted to contain a liquid and having a top with an opening therein, a casing provided with a downwardly extending annular flange which seats within the said opening, a strainer member carried by the flange of the casing and depending into the container, said casing having a sleeve extension, a motor within said sleeve extension, a fan within the casing and operated by the motor said casing being provided with an air outlet and an air inlet which extends through the said annular flange, and means for conducting air from without the container to adjacent the bottom of said container.

3. A vaporizing device comprising a container adapted to contain a liquid and having a top with an opening therein, means for conducting air from said opening to adjacent the bottom of the container, a fan having its suction inlet connected with the interior of the container for causing air to pass through said opening and through the air conducting means, and a hollow member extending within the casing, the walls of which are provided with openings, said member forming the passageway from the

interior of the container to the suction inlet of the fan.

4. A vaporizing apparatus comprising a container adapted to contain a liquid and having a top with an opening therein, means for conducting air to said opening to adjacent the bottom of the container, a fan for causing air to pass through the said opening and the air conducting means, and 10 a hollow strainer member of non-absorbent material connected with the suction inlet of the fan.

5. A vaporizing apparatus comprising a container adapted to contain a liquid, a 15 wall within the container extending approximately to the bottom of the container, the top of the container being provided with one or more openings which communicate with the space between the outside wall and 20 the inside wall of the container, a casing mounted upon the container, a suction device within said casing, means by which the casing member is mounted upon the top of the container, a hollow strainer member 25 associated with the casing and extending into the container from the top thereof.

6. A vaporizing device comprising a container adapted to contain a liquid and having a top with one or more openings therein, 30 an annular wall within the container which

depends from the top thereof inside the openings and extends nearly to the bottom of the container providing a space for conducting air from said openings to adjacent the bottom of the container, a movable plate 35 cooperating with the top of the container and adapted to control the passage of air through the openings therein, and a suction device connected with the space within the annular wall for causing air to pass through 40 said openings and air conducting space and through the body of liquid to the suction device.

7. A vaporizing apparatus comprising a container adapted to contain a liquid and 45 having a top with an opening therein, an annular wall within the container which depends from the top and extends nearly to the bottom thereby providing a space which communicates with the opening in the top 50 and will conduct air to adjacent the bottom of the container, a suction device connected with the interior of the container for causing air to pass through said opening and through the air conducting means, a conical 55 bottom member for said container to direct the fluid toward the edge of the container.

In testimony whereof, I hereunto affix my signature.

FRANK C. DORMENT.
